UNITED STATES PATENT OFFICE.

FREDERICK V. MATTON, OF RIVERTON, NEW JERSEY, ASSIGNOR TO CAMDEN IRON WORKS, OF CAMDEN, NEW JERSEY, A CORPORATION OF NEW JERSEY.

CENTRIFUGAL GAS-PURIFIER.

No. 866,375.

Specification of Letters Patent.

Patented Sept. 17, 1907.

Application filed April 16, 1907. Serial No. 368,599.

To all whom it may concern:

Be it known that I, FREDERICK V. MATTON, a subject of the King of Sweden, and a resident of Riverton, Burlington county, New Jersey, have invented certain 5 Improvements in Centrifugal Gas-Purifiers, of which the following is a specification.

My invention relates to gas purifiers of the centrifugal type, and the object of my invention is to provide a structure of the general character shown and described 10 in my former patent, No. 775,758, dated November 22, 1904, by the use of which I am enabled to secure increased capacity and greater efficiency.

My invention is fully shown in the accompanying drawings, in which:

15 Figure 1, is a longitudinal sectional view of a gas purifier embodying my invention, and Fig. 2, is a transverse sectional view of the same, taken on the line *a—a*, Fig. 1.

In the drawings herewith, the chambers for the inlet 20 and discharge of gas to be treated are indicated at 1 and 2, and except for slight changes in the position of the fans, it is immaterial whether the gas enters the chamber 1 and is discharged from the chamber 2, or takes a path in the opposite direction. In the present 25 instance the arrows indicate the direction of flow. The chambers 1 and 2 are continued in the form of elbows 3 and 4, respectively, which communicate with the interior of a central casing 5 having chambers 6 and 7, containing rotary fans 8 and 9 for effecting the 30 removal of tar or other impurities contained in the gas. The casing 5 is made in two parts which are conveniently separable so as to facilitate the manufacture of the same and the assembling of the various parts of the apparatus.

35 The fans are mounted on a shaft 10 adapted to suitable bearings 11 carried by the elbows 3 and 4, and in the present instance, each fan consists of a disk 12, having a series of long blades 13 on one side and slightly shorter blades 14 on the other side. These blades may 40 be of the same width throughout their length with tapering inner ends, and they are preferably so mounted as to just clear the walls of the casing.

Disposed within the casing 5 and surrounding the blades of each fan are rings 15 in which are mounted 45 fixed partitions 16 and 17, the partitions 16 being somewhat narrower than the partitions 17 and placed opposite the long blades 13 carried by the fan disks. The casing 5 is divided into the compartments or chambers 6 and 7 by a partition plate 18, having a central 50 annular opening 19, so that gas entering the structure from the inlet chamber 1 will be carried by the centrifugal action of the fan 8 into the chamber 6 of said casing; thence through the central opening 19 of the division plate 18 into the chamber 7 of the casing, and 55 from there it passes into the elbow 4 leading to the

chamber 2 from which latter it is discharged. The purpose of having the fan blades of different lengths is to insure the flow or circulation of the gas, and as this feature is fully explained in my former patent above referred to, there is no necessity for repetition 60 herein.

To discharge water or other liquid within the fan casing, I provide a main supply pipe 20 having three branches 21, 22 and 23; the branches 21 and 23 having nozzles 25 whereby the flow of such liquid may be directed from both sides toward the center of the casing, while the branch 22 communicates with a passage 26 65 formed within the division wall or plate 18 of the casing, from which it is discharged across said opening for engagement with the gas immediately passing from 70 one chamber to the next.

The structure is mounted upon a suitable foundation 30, having a central well 31 into which pipes 32 from the chambers 6 and 7 of the casing 5 discharge, and into which other pipes 33, leading, respectively, from the 75 inlet and outlet chambers 1 and 2, discharge; said well being provided, if desired, with an ordinary overflow pipe 34.

In the operation of the present form of purifier, the gas entering the chamber 1 is directed by the elbow 3 80 into the chamber 6 of the casing 5, where it is acted upon in the first instance by the blades 13 of the fan 8, which impart a whirling movement to the gas and cause any particles or liquid, such as tar or other impurities which are held in mechanical suspension in 85 the gas, to be thrown forcibly against the fixed partitions 16 of one side of the fan casing. The result of this action is that the bubbles are broken up and the liquid or solid particles are caused to adhere to said partition, from which when they have accumulated 90 in sufficient volume they drop and finally reach the bottom of the fan casing and are thence directed by the pipe 32 into the well 31. After the gas has been subjected to the beating action of the blades on one side of the first fan casing it passes to the opposite side 95 of the same and is there subject to a repetition of such action, and then passes through the opening 19 of the partition plate 18 into the chamber 7, for action by the blades of the fan 9 of the same character as that of the fan 8, and with corresponding results; the purified 100 gas finally escaping through the elbow 4 into the chamber 2 for discharge.

The edges of the rings carrying the partitions 16 and 17 overlap the fan blades, as shown in Fig. 1, and thereby prevent any of the gas from gaining access to the 105 outer chambers of the fan casing without coming under the influence of said fan blades.

The jets of water or other liquid projected onto the fans by the nozzles 25, and between the same from the passage 26 of the partition plate, serve to aid in the 11

separation of the tar or other impurities from the gas and wash from the fan blades and walls of the casing the impurities which have collected thereon, thus preventing the clogging of the fans by an undue accumulation of such impurities upon the blades.

I claim:

1. The combination, in a centrifugal gas purifier, of a rotatable shaft, a plurality of rotary fans mounted on said shaft, a casing inclosing said fans, partition means dividing the interior of said casing into a plurality of chambers each of which is occupied by a fan, said partition means being constructed to afford communication at a central point between said chambers, and provision for discharging water or other liquid across the communicating passage of said partition means.

2. The combination, in a centrifugal gas purifier, of a rotatable shaft, a plurality of rotary fans mounted on said shaft, a casing inclosing said fans, a partition wall dividing the interior of said casing into a plurality of chambers each of which is occupied by a fan, said partition having a central opening affording communication between said chambers, and provision for discharging water or other liquid across said opening.

3. The combination, in a centrifugal gas purifier, of a rotatable shaft, a plurality of rotary fans mounted on said shaft, each of said fans comprising a central plate carrying vanes of different lengths on opposite sides, a casing inclosing said fans, partition means dividing the interior of said casing into a plurality of chambers each of which is occupied by a fan, said partition means being constructed to afford communication between said chambers, and provision for discharging water or other liquid across the communicating passage of said partition means.

4. The combination, in a centrifugal gas purifier, of a rotatable shaft, a plurality of rotary fans mounted on said shaft, each of said fans comprising a central plate carrying vanes of different lengths on opposite sides, a casing inclosing said fans, a partition wall dividing the interior of said casing into a plurality of chambers each of which is occupied by a fan, said partition having an opening affording communication between said chambers, and provision for discharging water or other liquid across said opening.

5. The combination, in a centrifugal gas purifier, of a rotatable shaft, a plurality of rotary fans mounted thereon, a casing inclosing said fans, said casing having a division plate dividing the interior into a plurality of chambers, each occupied by a fan, said division plate having a vertical passage in its upper part, and a supply pipe communicating therewith whereby water or other liquid may be discharged across the opening of said division plate.

6. The combination, in a centrifugal gas purifier, of a rotatable shaft, a plurality of rotary fans mounted thereon, a casing inclosing said fans, said casing having a division plate dividing the interior into a plurality of chambers, each occupied by a fan, said fans having vanes of one length upon one side and shorter vanes on the other, said division plate having a vertical passage in its upper part, and a supply pipe communicating therewith whereby water or other liquid may be discharged across the opening of said division plate.

In testimony whereof, I have signed my name to this specification, in the presence of two subscribing witnesses.

FREDK. V. MATTON.
